DISPENSER

Robert Van Resen, New York, N. Y.

Application July 18, 1947, Serial No. 761,799

12 Claims. (Cl. 206—42)

1
The invention relates to a device for storing and dispensing articles. The device may be carried in the pocket and may be particularly useful for dispensing pills and the like. It may be adapted for dispensing various other articles such as candy, ball-bearings, chewing gum, capsules, pellets, tablets, eyelets, rivets and various other articles of various shapes.

The invention comprises a pair of plates which may lie in contact with each other and may have slots which may be in register with each other but may be movable to change the relation of the plates or slots. Thus in normal or closed position the slots may be closed so that articles may not be let out but the relative positions of the plates may be moved so as to allow an article to emerge and be ready to be distributed from the device when the plates are returned to normal position.

The invention may be embodied in various forms of apparatus. Without limiting the invention thereto, but in order to fully explain it, specific embodiments of the invention are described as shown in the accompanying drawings, in which Fig. 1 is a perspective view of one form of apparatus in normal position and provided with a backing or cover. Figs. 2, 3 and 4 are plan views of the device of Fig. 1 in different adjusted positions omitting the cover or backing. Fig. 5 is a transverse sectional view on the line 5—5 of Fig. 4. Fig. 6 is a perspective view of an optional form of device. Fig. 7 is a plan view of the device of Fig. 6 omitting the cover or backing. Fig. 8 is a perspective view of another form of device. Fig. 9 is a perspective of another form of device.

The device of Figs. 1 to 5 may include two plates 15 and 16 mounted on a backing 17 which may have a portion 18 to fold over and engage one edge of the plates and lie on the top of the plates. The position in which the device may be held or arranged is not important but for convenience of reference words of position or direction referring to the devices as shown in the drawings may be used without limiting the invention to such positions or directions. The plate 15 may be referred to as the inner or lower plate and 16 as the outer or upper plate. In each of the plates may be provided slots or apertures. The slot 19 in the plate 16 may be slightly wider than the article 20 to be handled and long enough to hold a plurality of such articles—six being shown. The slot 21 in the plate 15 may be somewhat wider than the slot 19. The slots 19 and 21 are shown as extending entirely through the plates 15 and 16 and this may be desirable and

the combined thickness of the plates 15 and 16 may be slightly more than the diameter of an article 20 as indicated in Fig. 5. The slots need not extend entirely through the plates, but the combined depths of the two slots will be slightly more than the diameter of an article. The depth of each plate or of each slot may be much or little less than the diameter of an article so that the articles may never be free of either slot. Preferably and as shown, each slot may have a depth of slightly more than half the diameter of an article. The plates 15 and 16 may be held together so that there may be relative movement between them in a lateral direction. For this purpose is shown an appropriately positioned pivot member 22.

The top slot 19 has a curve 23 at its lower end which merges into an outlet portion 26 shown as directed to and opening from the left side of the plate 16. As shown in Fig. 4 with the members in normal position, the slot 21 underlies the slot 19 and is wider than it. The right side of slot 21 is substantially under the right side of slot 19, but the left side of slot 21 is further to the left so that as the plate 16 is pivoted to the position shown in Fig. 2, the articles are carried by the movement of the slot 19. In the right side of the slot 21 and just above the curve 23 is a projection 24 extending to the left to a point nearer the left side of the slot 19 than the diameter of an article, so that the article may not pass between the projection 24 and the side of the slot 19. Thus when closed, the articles are locked in the device, as the upper five articles are shown in Fig. 4. On the left side of the slot 21 there is another projection 25 extending to the right so that it does not impede an article when in normal position (Fig. 4) but when the plate 16 swings on its pivot (Figs. 2 and 3) the projection 25 extends so near the right side of the slot 19 that it impedes the exit of an article since it leaves a space less than the diameter of an article. Below the projection 25, the slot in plate 15 curves into an outlet portion 27 which underlies the outlet portion 26 when in normal position so as to let an article out for distribution, as shown in Fig. 4.

When the plate 16 is pivoted to the left, as shown in Fig. 2, the articles are freed from the projection 24 and fall to be held or stopped by the projection 25. As the plate 16 is returned toward the right, as shown in Fig. 3, the projection 24 enters the group of articles stopping all but one, which is held by the projection 25 until the apparatus reaches the normal position when the projection 25 releases the bottom article.

which has been released from 24 for distribution or exit as shown in Fig. 4. This manipulation may be repeated as frequently as desired. As shown, the space between 25 and 26 is only sufficient for one article at a time. If this space is lengthened two or more may be released at a time.

If open, it may be convenient to place over the slot 19 a sheet of material to act as a cover and retain and keep from deterioration the articles. This may be a transparent sheet shown at 28 as extending over the entire surface of the plate 16.

The portion 18 of the backing may be folded over onto the plate 16 or the sheet 28 and held in any suitable way to protect the distributing device and act as an extra closing means for outlet 26, 27.

In Figs. 6 and 7 a modification is shown in which the outer plate 16a with cover sheet 28a rests on the inner plate 15a which rests on a backing 17a having a closing flap 18a engaging a second closing flap 18b. Here the slots do not turn as in Figs. 1 to 6, but have the outlet at the end of the device more directly connected with the main slots. The plates 15a and 16a are pivoted toward their tops at 22a and the form of the lower slot 21a may be modified accordingly, as shown.

In Fig. 8 is shown a modification in which a portion of the outer plate marked 26 may be permanently fixed in place on the inner plate 15b. The outer plate 26 is cut out at 29 on a circular line to receive for turning a plate 36 corresponding to the outer plate 16 of Fig. 1. An aperture 37 is formed to allow the member 36 to turn or pivot and a cut-out sheet 30 may be turned down to overlie the circular cut-out portion 29 so as to hold the plate 36 from falling out of place. A cover plate 28b may be applied to the plate 36 to hold the articles in the slot.

In Fig. 9 is shown a modification in which the slots 19d and 21d in both inner and outer plates 15c and 16c are larger and hold the articles in a flat sheet instead of the single file row of the device of Figs. 1 to 8. The projection 24d arranged like the projection 24 in Figs. 1, etc., controls the dispensing of the articles when the outer plate 16c is swung on the pivot 22d. A handle 31 is provided for manipulation of the plate 16c. A cover sheet 28d may be provided for control and inspection of the articles in the device.

The operations for letting out the articles may be reversed and articles inserted to fill the device for reuse if desired.

Any suitable means for allowing or effecting relative movement of the plates may be employed, as the invention is not confined to the pivot arrangement illustrated.

The device may be made of any suitable material for temporary use or for repeated use. The plates and the backing or cover may be of card-board, plastic, fabric, leather, or any other suitable material. The sizes, shapes and forms of the device or its parts may be varied without departing from the invention.

I claim as my invention:

1. In a device for dispensing articles, a backing, an inner plate on the backing thicker than one-half the thickness of an article, an outer plate pivoted to the inner plate to swing thereon and thicker than one-half the thickness of an article, a transparent cover on the outer plate, a top slot in the outer plate as long as the width of a plurality of articles and slightly wider than the width of an article, a free outlet for the top slot at the side of the plate, a curve in the top slot

toward its outlet, a bottom slot in the inner plate underlying the top slot and extending in width from one side of the top slot in unswung position to the other side of the top slot in swung position, a free outlet for the bottom slot in register with the outlet for the top slot when it is in unswung position, a curve in the bottom slot toward its outlet, a projection at the top of the curve in the bottom slot extending less than the width of an article from the opposite side of the upper slot when in unswung position but more than the width of an article from the opposite side of the upper slot when in swung position, and a second projection from the other side of the lower slot and more than the width of an article nearer the outlet than the first mentioned projection, the second projection being less than the width of an article from the opposite side of the upper slot when in swung position but more than the width of an article from the opposite side of the upper slot when in unswung position.

2. In a device for dispensing articles, an inner plate thicker than one-half the thickness of an article, an outer plate pivoted to swing on the inner plate and thicker than one-half the thickness of an article, a top slot in the outer plate as long as the width of a plurality of articles and slightly wider than the width of an article, a free outlet for the top slot, a curve in the top slot toward its outlet, a bottom slot in the inner plate underlying the top slot and extending in width from one side of the top slot in unswung position to the other side of the top slot in swung position, a free outlet for the bottom slot in register with the outlet for the top slot when it is in unswung position, a curve in the bottom slot toward its outlet, a projection at the top of the curve in the bottom slot extending less than the width of an article from the opposite side of the upper slot when in unswung position but more than the width of an article from the opposite side of the upper slot when in swung position, and a second projection from the other side of the lower slot and more than the width of an article nearer the outlet than the first mentioned projection, the second projection being less than the width of an article from the opposite side of the upper slot when in swung position but more than the width of an article from the opposite side of the upper slot when in unswung position.

3. In a device for dispensing articles, an inner plate thicker than one-half the thickness of an article, a member overlying part of the inner plate, an outer plate pivoted in the overlying member to swing on the inner plate and thicker than one-half the thickness of an article, a top slot in the outer plate as long as the width of a plurality of articles and slightly wider than the width of an article, a free outlet for the top slot at the side of the plate, a curve in the top slot underlying the top slot and extending in width from one side of the top slot in unswung position to the other side of the top slot in swung position, a free outlet for the bottom slot in register with the outlet for the top slot when it is in unswung position, a curve in the bottom slot toward its outlet, a projection at the top of the curve in the bottom slot extending less than the width of an article from the opposite side of the upper slot when in unswung position but more than the width of an article from the opposite side of the upper slot when in swung position, and a second projection from the other side of the lower slot and more than the width of an article nearer the outlet than the first mentioned projection, the second projection being less than the width of an article from the opposite side of the upper slot when in swung position but more than the width of an article from the opposite side of the upper slot when in unswung position.

outlet than the first mentioned projection, the second projection being less than the width of an article from the opposite side of the upper slot when in swung position but more than the width of an article from the opposite side of the upper slot when in unswung position.

4. In a device for dispensing articles, an inner plate, an outer plate pivoted to swing across the inner plate, each plate being thinner than the thickness of an article but the combined thickness of the plates being greater than the thickness of an article, a stop slot in the outer plate as long as the width of a plurality of articles and slightly wider than the width of an article, a free outlet for the top slot of the side of the plate, a curve in the top slot toward its outlet, a bottom slot in the inner plate underlying the top slot and extending in width from one side of the top slot in unswung position to the other side of the top slot in swung position, a free outlet for the bottom slot in register with the outlet for the top slot when it is in unswung position, a curve in the bottom slot toward its outlet, a projection at the top of the curve in the bottom slot extending less than the width of an article from the opposite side of the upper slot when in unswung position but more than the width of an article from the opposite side of the upper slot when in swung position, and a second projection from the other side of the lower slot and more than the width of an article nearer the outlet than the first mentioned projection, the second projection being less than the width of an article from the opposite side of the upper slot when in unswung position.

5. In a device for dispensing articles, an inner plate, an outer plate pivoted to swing across the inner plate, each plate being thinner than the thickness of an article but the combined thickness of the plates being greater than the thickness of an article, a top slot in the outer plate sufficiently long and wide to receive a plurality of articles, a free outlet for the top slot, a curve in the top slot toward its outlet, a bottom slot in the inner plate underlying the top slot and sufficiently long and wide to receive a plurality of articles, a free outlet for the bottom slot in register with the outlet for the top slot when it is in unswung position, a curve in the bottom slot toward its outlet, a projection at the top of the curve in the bottom slot extending less than the width of an article from the opposite side of the upper slot when in unswung position but more than the width of an article from the opposite side of the upper slot when in swung position, and a second projection from the other side of the lower slot and more than the width of an article nearer the outlet than the first mentioned projections, the second projection being less than the width of an article from the opposite side of the upper slot when in swung position but more than the width of an article from the opposite side of the upper slot when in unswung position.

6. In a device for dispensing articles, an inner plate, an outer plate pivoted to the inner plate to swing thereon, a transparent cover on the outer plate, a top slot in the outer plate as long as the width of a plurality of articles and slightly wider than the width of an article, a free outlet for the top slot, a bottom slot in the inner plate underlying the top slot and extending in width from one side of the top slot in unswung position to the other side of the top slot in swung position, a

free outlet for the bottom slot in register with the outlet for the top slot when it is in unswung position, each slot being of less depth than the thickness of an article but the combined depths of the slots being greater than the thickness of an article, a projection in the bottom slot extending less than the width of an article from the opposite side of the upper slot when in unswung position but more than the width of an article from the opposite side of the upper slot when in unswung position, and a second projection from the other side of the lower slot and more than the width of an article nearer the outlet than the first mentioned projection, the second projection being less than the width of an article from the opposite side of the upper slot when in unswung position, and a second projection from the other side of the lower slot and more than the width of an article nearer the outlet than the first mentioned projection, the second projection being less than the width of an article from the opposite side of the upper slot when in unswung position.

7. In a device for dispensing articles, an inner plate, an outer plate pivoted to the inner plate to swing thereon, a transparent cover on the outer plate, a top slot in the outer plate as long as the width of a plurality of articles and slightly wider than the width of an article, a free outlet for the top slot, a bottom slot in the inner plate underlying the top slot and extending in width from one side of the top slot in unswung position to the other side of the top slot in swung position, a free outlet for the bottom slot in register with the outlet for the top slot when it is in unswung position, each slot being of less depth than the thickness of an article but the combined depths of the slots being greater than the thickness of an article, and a projection in the bottom slot extending less than the width of an article from the opposite side of the upper slot when in unswung position but more than the width of an article from the opposite side of the upper slot when in unswung position.

8. In a device for dispensing articles, an inner plate, an outer plate mounted to move across the inner plate, each plate being thinner than the thickness of an article but the combined thickness of the plates being greater than the thickness of an article, a top slot in the outer plate sufficiently long and wide to receive a plurality of articles, a free outlet for the top slot, a curve in the top slot toward its outlet, a bottom slot in the inner plate underlying the top slot and sufficiently long and wide to receive a plurality of articles, a free outlet for the bottom slot in register with the outlet for the top slot when it is in unswung position, and a projection in the bottom slot extending less than the width of an article from the opposite side of the upper slot when in unswung position but more than the width of an article from the opposite side of the upper slot when in unswung position.

9. In a device for dispensing articles, an inner plate, an outer plate, means for mounting the plates for lateral relative movement, each plate being thinner than the thickness of an article but the combined thickness of the plates being greater than the thickness of an article, a top slot in the outer plate as long as the width of a plurality of articles and wider than the width of an article, a free outlet for the top slot at the side of the plate, a curve in the top slot toward its outlet, a bottom slot in the inner plate underlying the top slot and extending in width from one side of the top slot in normal position to the other side of the top slot in moved position, a free outlet for the bottom slot in register with the top slot when it is in normal posi-

tion, a curve in the bottom slot toward its outlet, a projection at the top of the curve in the bottom slot extending less than the width of an article from the opposite side of the upper slot when in normal position but more than the width of an article from the opposite side of the upper slot when in moved position; and a second projection from the other side of the lower slot and more than the width of an article nearer the outlet than the first mentioned projection, the second projection being less than the width of an article from the opposite side of the upper slot when in moved position but more than the width of an article from the opposite side of the upper slot when in normal position.

10. In a device for dispensing articles, an inner plate, an outer plate, each plate being thinner than the thickness of an article but the combined thickness of the plates being greater than the thickness of an article, means for mounting the plates for lateral relative movement, a top slot in the outer plate sufficiently long and wide to receive a plurality of articles, a free outlet for the top slot, a bottom slot in the inner plate underlying the top slot and sufficiently long and wide to receive a plurality of articles, a free outlet for the bottom slot in register with the outlet for the top slot when it is in normal position, and a projection toward the bottom of the bottom slot extending less than the width of an article from the opposite side of the upper slot when in normal position but more than the width of an article from the opposite side of the upper slot when in moved position.

11. In a device for dispensing articles, an inner plate, an outer plate, means for mounting the plates for lateral relative movement, a top slot in the outer plate as long as the width of a plurality of articles and wider than the width of an article, a free outlet for the top slot, a bottom slot in the inner plate underlying the top slot and

- greater in length and width than the width of an article, a free outlet for the bottom slot in register with the outlet for the top slot when it is in normal position, each slot being of less depth than the thickness of an article but the combined depths of the slots being greater than the thickness of an article, a projection in the bottom slot extending less than the width of an article from the opposite side of the upper slot when in normal position but more than the width of an article from the opposite side of the upper slot when in moved position; and a second projection from the other side of the lower slot and more than the width of an article nearer the outlet than the first mentioned projection, the second projection being less than the width of an article from the opposite side of the upper slot when in moved position but more than the width of an article from the opposite side of the upper slot when in normal position.
12. In a device for dispensing articles, an inner plate, an outer plate, means for mounting the plates for lateral relative movement, a top slot in the outer plate as long as the width of a plurality of articles and wider than the width of an article, a free outlet for the top slot, a bottom slot in the inner plate underlying the top slot and greater in length and width than the width of an article, a free outlet for the bottom slot in register with the outlet for the top slot when it is in normal position, each slot being of less depth than the thickness of an article but the combined depths of the slots being greater than the thickness of an article, and a projection in the bottom slot extending less than the width of an article from the opposite side of the upper slot when in normal position but more than the width of an article from the opposite side of the upper slot when in moved position.

ROBERT VAN ROSEN.
